UNITED STATES PATENT OFFICE

1,992,850

FABRIC GRIPPER

Harry C. Aberle, Jenkintown, Pa., assignor to
 H. C. Aberle Company, Philadelphia, Pa., a
 corporation of Pennsylvania

Application September 7, 1932, Serial No. 632,057

14 Claims. (Cl. 66—147)

This invention relates to a device for gripping the welt of a full-fashioned stocking blank being or to be made on a flat full-fashioned hosiery knitting machine, and is particularly adaptable 5 in connection with woven welts having a spaced warp affording a readily discernible line for topping the woven welt onto the needles of the knitting machine, as disclosed in the applicant's prior United States Letters Patent No. 1,860,272 dated

10 May 24, 1932.

The invention is particularly adaptable to elastic welts of the general type disclosed in said patent, and the primary object of the invention is to grip the welt at all points across the full 15 width thereof in order that uniform tension will be applied at all the needles knitting the stocking blank to the welt.

In the accompanying drawing:

Fig. 1 is a perspective view of a device made 20 and operating in accordance with the principles of the present invention;

Fig. 2 is an enlarged sectional elevation taken on the line 2—2, Fig. 1; and

Fig. 3 illustrates the welt gripper being applied 25 to a welt subsequent to the topping of the welt along one of its edges to the needles of a flat full-fashioned hosiery knitting machine adapted to knit the leg of a stocking onto the welt.

The device comprises a tube 1 having a handle 30 2 comprising a pair of laterally extending arms 3 integrally connected by a bar 4 paralleling the tube 1, the arms 3, 3 in the present instance being rigidly secured to the tube 1 in any desired manner as by soldering, welding, brazing, etc.

Within the tube 1 is rotatably mounted a bar 35 5 having a slot 6 which is arranged to be aligned with a corresponding slot 7 extending longitudinally of the tube 1 for the reception of one edge of the welt W, as clearly illustrated in Fig. 3.

The clamp bar 5 is provided with a cam surface 40 8 which, when the tube 1 is turned relative to the clamp bar 5 from the fabric-receiving position shown in Fig. 3 to the fabric-gripping position shown in Fig. 2, clamps the welt W against the inner surface 9 of an overhanging portion 10 of the tube 1 adjacent one side of the slot 7 therein, the overhanging portion 10 of the tube 1 being more or less resilient and acting as a spring clip to press the welt W firmly against the cam surface 8 of the clamp bar 5, whereby the welt W is snubbed around the edge 11 of the slot 7 in the tube 1 and the edge 18 of the bar 5 in the form of an S turn as shown in Figs. 1 and 2.

The clamp bar 5 is provided with a handle 12 45 comprising arms 13, 13, in the present instance

having turned ends 14, 14 secured in a groove 15 in the bar 5 while the opposite ends of the arms 13, 13 project laterally from the bar 5 and are integrally connected by a cross bar 16 extending parallel to the bar 5.

In operation one edge W¹ of the welt W is topped onto the needles N of the knitting machine and with the welt held in a substantially horizontal plane the edge W² of the welt is placed within the aligned slot 7 of the tube 1 and groove 10 6 of the bar 5, as seen in Fig. 3. The handle 2 of the tube 1 is then turned from the position shown in Fig. 3 to that shown in Fig. 2 wherein the handle bar 4 of the tube handle 1 is immediately under the handle bar 16 of the handle 12 15 5 of the clamp bar 5, which rotates the tube 1 about the clamp bar 5 and effects gripping and snubbing of the welt W as noted above.

The handle bars 4 and 16 are then held in the fabric gripping position of Fig. 2 by a hook or 20 other fastening 20 secured to one end of the take up strap 21 of the knitting head, the opposite end of the strap being secured to the spring loaded take-up roll of the knitting head in the usual manner and not shown in the present 25 instance.

Relative longitudinal movement between the tube 1 and clamp bar 5 is prevented by the arms 13, 13 of the handle 12 of the clamp bar 5 operating in circumferential segmental relatively 30 spaced slots 17, 17 formed in the tube 1 as clearly shown in Figs. 1, 2 and 3.

I claim:—

1. A fabric gripper for use with a flat knitting machine, said gripper comprising a pair of 35 coaxially arranged relatively rotatable rectilinear elements slotted longitudinally for receiving one edge of a piece of fabric having its opposite edge attached to a bank of needles in said machine, said elements having fabric engaging surfaces 40 respectively disposed adjacent the slots therein for cooperatively gripping the fabric therebetween in overlapping relation of each other upon relative rotation between said elements.

2. A fabric gripper for use with a flat knitting machine, said gripper comprising a tubular element having a longitudinally extending slot for receiving one edge of a piece of fabric having its opposite edge attached to a bank of needles in 45 said machine, said tubular element having a fabric engaging surface adjacent said slot, and an element rotatably mounted in said tubular member and provided with a fabric engaging surface adapted to cooperate with that of said tubular element for gripping the fabric therebetween upon 50 55

relative rotation of one of said elements with respect to the other thereof.

3. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements.

4. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements, and means for locking said elements in said fabric gripping relation.

5. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements, a handle on said second element, a handle on said tubular element, and means for locking said handles to secure said elements in said fabric gripping position.

6. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements, a handle on said second element, a handle on said tubular element, and means arranged to engage said handles simultaneously to lock said elements in said fabric gripping relation.

7. A fabric gripper for use with a flat knitting machine, said gripper comprising a tubular element provided with a longitudinally extending slot and a fabric engaging surface adjacent said

slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements, a handle on said second element, a handle in said tubular element, and means for securing said handles together to lock said elements in said fabric gripping relation and to attach said gripper to a tensioning mechanism of said machine.

8. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface adjacent said slot for cooperation with the fabric engaging surface of said tubular element to grip the fabric therebetween upon relative rotation of said elements, a handle on said second element, a handle in said tubular element, and means for securing said handles together to lock said elements in said fabric gripping relation and to attach said gripper to a tensioning mechanism of said machine.

9. A fabric gripper for use with a flat knitting machine, said gripper comprising a tubular element provided with a longitudinally extending slot and a fabric engaging surface adjacent said slot, a second element rotatably mounted in said tubular element and provided with a longitudinally extending groove arranged to register with the slot in said tubular element for receiving one edge of a piece of fabric having its opposite edge attached to a bank of needles in said machine said second element having a fabric engaging surface of said tubular element to grip the fabric therebetween upon relative rotation of said elements a handle on said second element, a handle on said tubular element, a hook arranged to engage said handles simultaneously to lock said elements in said fabric gripping relation.

10. A fabric gripper for use with a flat knitting machine having a bank of needles of predetermined width, said gripper comprising a pair of relatively movable elements each provided with a rectilinear edge and an adjacent fabric-gripping surface substantially as long as the width of the bank of needles for receiving and engaging therebetween and substantially parallel to the bank of needles a portion of a fabric being knit by said needles, means for moving one of said elements relative to the other of said elements to move said edge and surface thereof in a path substantially coincident with and forming a continuation of said surface to a position wherein the edge of each of said elements is disposed over the surface of the other element inwardly from the edge of said other element, and means maintaining said edges substantially parallel one to

the other throughout said relative movement between said elements.

11. A fabric gripper for use with a flat knitting machine having a bank of needles of predetermined width, said gripper comprising a pair of relatively movable elements each provided with a rectilinear edge and an adjacent fabric-gripping surface substantially as long as the width of the bank of needles for receiving and engaging therebetween and substantially parallel to the bank of needles a portion of a fabric being knit by said needles, means for moving one of said elements relative to the other of said elements to move said edge and surface thereof in a path substantially coincident with and forming a continuation of said surface to a position wherein the edge of each of said elements is disposed over the surface of the other element inwardly from the edge of said other element with the fabric gripped between said surfaces, and means for locking said elements in said fabric-gripping position, said locking means serving as a means for attaching the gripper to a fabric-tensioning and take-up mechanism of said machine.

12. A fabric gripper for use with a flat knitting machine having a bank of needles of predetermined width, said gripper comprising a pair of relatively movable elements each provided with a rectilinear edge and an adjacent fabric-gripping surface substantially as long as the width of the bank of needles for receiving and engage therebetween and substantially parallel to the bank of needles a portion of a fabric being knit by said needles, means for moving one of said elements relative to the second of said elements to move said edge and surface of the first element in a path substantially coincident with and forming a continuation of said surface to a position wherein the edge of each of said elements is disposed over the surface of the other element inwardly from the edge of said other element with the fabric gripped between said surfaces, the fabric-engaging surface of the second element being inclined to the path of movement of the fabric-engaging edge and surface of the first relatively movable element for increasing the grip of said surfaces on said fabric in accordance with the relative movement between said surfaces.

13. A fabric gripper for use with a flat knitting machine having a bank of needles of predetermined width, said gripper comprising a pair of pivotally connected relatively movable elements each provided with a rectilinear edge and an adjacent fabric-gripping surface substantially as long as the width of the bank of needles for receiving and engaging therebetween and substantially parallel to the bank of needles a portion of a fabric being knit by said needles, and means for rocking one of said elements relative to the other of said elements to move said edge and surface thereof in a circular path substantially coincident with and forming a continuation of said surface and swung from the axis of the pivotal connection between said elements to a position wherein the edge of each of said elements is disposed over the surface of the other element circumferentially inwardly from the edge of said other element.

14. A fabric gripper for use with a flat knitting machine having a bank of needles of predetermined width, said gripper comprising a pair of relatively movable elements each provided with a rectilinear edge and an adjacent fabric-gripping surface substantially as long as the width of the bank of needles for receiving and engaging therebetween and substantially parallel to the bank of needles a portion of a fabric being knit by said needles, means for moving one of said elements relative to the other of said elements to move said edge and surface thereof in a path substantially coincident with and forming a continuation of said surface to a position wherein the edge of each of said elements is disposed over the surface of the other element inwardly from the edge of said other element, and means extending substantially at right angles to said surfaces for placing said fabric under tension and maintaining said surfaces substantially perpendicular to the plane of the portion of the fabric lying between the needles and the gripper.

HARRY C. ABERLE.
